UNITED STATES PATENT OFFICE

HERMAN E. SCHULSE, OF WILMINGTON, DELAWARE, ASSIGNOR TO UNICLOX CORPORATION, A CORPORATION OF DELAWARE

DESIGN FOR A COMBINED TERRESTRIAL GLOBE FRAME, CLOCK CASING, AND SUPPORT THEREFOR

Application filed April 11, 1931. Serial No. 39,453. Term of patent 3½ years.

To all whom it may concern:

Be it known that I, Herman E. Schulse, a citizen of the United States, and residing at Wilmington, in the county of New Castle and State of Delaware, have invented a new, original, and ornamental Design for a Combined Terrestrial Globe Frame, Clock Casing, and Support Therefor, of which the following is a specification, reference being had to the accompanying drawings, forming part hereof.

Fig. 1 is a front view of a combined terrestrial globe frame, clock casing and support therefor, showing my new design; and

Fig. 2 is a side perspective view of the same.

I claim:

The ornamental design for a combined terrestrial globe frame, clock casing, and support therefor, as shown.

HERMAN E. SCHULSE.
